By Karl Grunig
his Attorney*

UNITED STATES PATENT OFFICE.

CHARLES KRES, OF CLEVELAND, OHIO, ASSIGNOR TO THE FORMAN BASSETT COMPANY, A CORPORATION OF OHIO.

DESIGN FOR SAFETY PAPER.

61,166.

Specification for Design.

Patented July 4, 1922.

Application filed February 23, 1921. Serial No. 447,334. Term of patent 3½ years.

To all whom it may concern:

Be it known that I, CHARLES KRES, a citizen of the United States, and a resident of Cleveland, Ohio, have invented certain new, original, and ornamental Design for Safety Paper, of which the following is a specification, reference being had to the accompanying drawing.

The accompanying drawing illustrates the design applied to a portion of safety paper.

I claim as my invention:

The ornamental design for safety paper surface, as shown.

CHARLES KRES.
